(57) CLAIM

The ornamental design for a fire pit boot, as shown and described.

DESCRIPTION

FIG. 1 is a front view of a fire pit boot showing the new design;

FIG. 2 is a back view of the fire pit boot;

FIG. 3 is a front perspective view of the fire pit boot;

FIG. 4 is a back perspective view of the fire pit boot;

FIG. 5 is a second side view of the fire pit boot; and,

FIG. 6 is a first side view of the fire pit boot.

The broken lines depict portions of the fire pit boot that form no part of the claimed design.
